SWITCH POSITION INDICATORS

Albert F. Hopkins, Jr., Alexandria, Va.

Application April 23, 1954, Serial No. 425,340

3 Claims. (Cl. 200—167)

(Granted under Title 35, U. S. Code (1952), sec. 266)

The invention described herein may be manufactured and used by or for the Government of the United States for governmental purposes without the payment to me of any royalty thereon, in accordance with the provisions of 35 United States Code (1952) section 266.

This invention relates to electric switches and more particularly to indicators for determining the position of such electric switches.

Heretofore indicating means for showing whether a switch was in the "on" or "off" position have been primarily of the type utilizing an electric light bulb. While advantageous for the light providing value for finding the switch in the dark, these indicators suffer from the disadvantage of being rather expensive to manufacture. Furthermore these indicators are subject to power failures and to light bulb burnout and for these reasons lack the dependability desired in many present-day switching applications. With the use of phosphorescent or fluorescent paint applicant's invention has many of the advantages of the light bulb indicator and the added advantages of simple mechanical construction and ease of installation.

The object of this invention is to provide a simple, inexpensive switch position indicator.

Another object of this invention is to provide a switch position indicator that is simple and easy to install.

Another object of this invention is to provide a switch position indicator adapted to be utilized with the standard household light switch.

Another object is to provide a switch position indicator adapted to be utilized with the standard household light switch faceplate.

A further object of this invention is to provide a purely mechanical visual indicator for electric switches.

Very often it is desirable to have adjacent an electric switch a visual indication of whether the switch is in the "on" or "off" position. This is particularly true in applications in which the device controlled by the switch cannot be directly seen or heard.

This invention provides a switch indicator of extremely simple construction capable of being fitted directly over the face of the standard household light switch faceplate. Furthermore it provides a sliding indicator, directly actuated by the switch lever, which may be used to indicate by color either the "on" or "off" position of a switch. The indicator lends itself to quick installation and requires no modification of the faceplate.

Other uses and advantages of the invention will become apparent upon reference to the specification and drawings.

Figure 1 shows a front view of the indicator as it appears when attached to the faceplate of a standard household light switch.

Figure 2 shows a cross section along 2—2 of Figure 1.

Figure 3 is a front view of the indicator slide holder member.

Figure 4 shows a front view of the indicator sliding member.

A slide holder member 1 is adapted to be supported on a switch face plate by means of screw holes 2. These

holes are positioned to coincide with the screws used to attach the faceplate of a standard household light switch. The distance between the holes of a standard faceplate is substantially uniform throughout the United States and is equal to 2½ inches. Around holes 2 are counterbored or depressed portions 3 of holder 1. These depressions permit the free passage of slider 7 over the heads of ordinary screws used to hold the indicator and faceplate to the switch.

As best shown in Figure 3 holder 1 includes aperture 6 which allows free movement of the switch lever with respect to the holder. Holder 1 further includes colored areas 8 which serve to give visual indication of the position of the switch lever. These sections may be any color, preferably red, and this coloring may be applied in any well known manner. A form of phosphorescent paint may be used in situations in which it is desirable to utilize applicant's invention in unlighted places.

Slider 7 is positioned adjacent holder 1 and retained in sliding engagement with the holder by means of crimped or turned over edges 9. All four edges of holder 1 may be crimped over to retain slider 7 but merely crimping edges 9 is obviously sufficient to retain the slider against the holder.

Slider 7 includes aperture 11 which coincides with a portion of aperture 6 in holder 1. Aperture 11 permits the slider to be slipped over a switch lever and causes sliding motion to be imparted to the slider upon manipulation of the lever. Slits 12 in slider 7 permit the colored areas 8 to be seen by an observer when the slider is in one of its two positions corresponding to either the "on" or "off" position of the switch lever. When the switch lever is in the other position the areas 8 are covered by the solid portions of the slider 7. It is generally preferred that the red indications will be showing when the switch is in the up or "on" position, as illustrated in Figure 1. However it is apparent that by merely unscrewing the indicator and turning it upside down the red areas would be visible to an observer when the switch lever is in the lower or "off" position.

The indicator may be constructed of any suitable light weight material such as aluminum, plastic, cardboard, etc. It is simple to manufacture and may be used with any standard switch faceplate. The overall dimensions of the embodiment constructed by applicant are, length 3 inches, and width 1½ inches.

If so desired one or both of slits 12 may be omitted. When either the upper slit or both slits 12 are omitted from the slider the areas 8 may be of different colors indicating the relative positions of the switch. Merely omitting the lower slit 12 will not alter the operation of the device if slider 7 is made correspondingly of shorter length.

Another obvious modification of applicant's invention would be to reverse the position of the parts, i. e., place the slider between the holder and the faceplate. In such a case the slider would carry the coloring and the holder would be provided with viewing apertures.

It will be apparent that the embodiments shown are only exemplary and that various modifications can be made in construction and arrangement within the scope of my invention as defined in the appended claims.

What is claimed is:

1. A switch position indicator adapted to be placed over the faceplate of a standard lever type household light switch comprising a flat rectangular holder member having an elongated rectangular center aperture for receiving the switch lever, said holder member having counterbored holes positioned to coincide with the screw holes in said faceplate, the longer edges of said holder member being folded over to provide spaced channels, colored indicia

on a portion of said holder member and a rectangular slider member having a centrally located rectangular aperture of such dimensions as to closely engage the base of the lever of said switch, the edges of the longer sides of said slider member being retained in said spaced channels, said slider member being movable by said lever to selectively cover and uncover said indicia in accordance with the position of said switch.

2. A switch position indicator as defined in claim 1 in which said indicia is fluorescent.

3. A switch position indicator adapted to be placed over the faceplate of a standard lever-type household light switch comprising a flat rectangular holder member having an elongated rectangular center aperture for receiving the switch lever, said holder member having holes positioned to coincide with the screw holes in said faceplate,

the longer edges of said holder member being folded over to provide spaced channels, a rectangular slider member having a centrally located rectangular aperture of such dimensions as to closely engage the base of the lever of said switch, the edges of the longer sides of said slider member being retained in said spaced channels, indicia on a portion of one of said members, said slider member being movable by said lever to selectively expose said indicia in accordance with the position of said switch.
